UNITED STATES PATENT OFFICE.

ABRAHAM FEIL AND SAMUEL L. SCHWARTZ, OF NEW YORK, N. Y.

FABRIC-HOLDING FRAME FOR EMBROIDERING-MACHINES.

1,278,451.

Specification of Letters Patent. Patented Sept. 10, 1918.

Application filed April 23, 1918. Serial No. 230,207.

To all whom it may concern:

Be it known that we, ABRAHAM FEIL, a citizen of the United States of America, and SAMUEL L. SCHWARTZ, a subject of the King 5 of Rumania, both residing at New York, in the county of New York and State of New York, have invented certain new and useful Improvements in Fabric-Holding Frames for Embroidering-Machines, of which the 10 following is a specification.

This invention has reference to attachments on embroidering machines of the Groebli or Zahn type with a vertical frame in front of which sets of needles and other 15 implements move horizontally across the fabric usually stretched over the plane of the frame.

When short pieces of fabric such as parts 20 of ladies' waists or the like are to be embroidered, then in order to perform the embroidery work on all pieces simultaneously and with great accuracy as to the design required and the particular location of the embroidery, it becomes necessary to use a separate or auxiliary frame which is suspended 25 from or supported in the frame of the embroidery machine.

Our invention deals particularly with the 30 construction of such auxiliary frame for the support of several small pieces of fabric on which embroidery is to be produced.

One object of our invention is to so construct the said frame that the pieces of fabric can be easily attached to and removed 35 from said frame and can be properly adjusted to a position which will allow of the designs being produced on the several pieces of goods at the places desired.

Another object of our invention is to provide 40 means which will serve as a guide to the operator to enable him to arrange the needles or other implements in the proper position with respect to the pieces of fabric.

A further object of our invention is to 45 provide means for gathering and concealing the ends or edges of the pieces of fabric which, in case the latter are cut on a bias, as usually are the parts of a lady's waist, would, when stretched in the auxiliary frame, be 50 liable to project over the face of the fabric and interfere with the embroidery work performed thereon.

And a further object of our invention is to 55 provide locking means for holding the above named means in position.

With these and other objects in view, our

invention consists in the combination, arrangement and construction of parts as will be hereinafter more fully described and set forth in the appended claims. 60

In the accompanying drawings which form part of this specification and in which similar reference characters denote corresponding parts, Figure 1 is a rear elevation of the auxiliary frame; Fig. 2 is a partial 65 front elevation of the auxiliary frame with some parts removed; Fig. 3 is an enlarged rear view of a part of the frame with a piece of fabric shown as attached thereto; Fig. 4 is an end view of the part shown in Fig. 3; 70 Fig. 5 is a section on line 5—5 of Fig. 3; Fig. 6 is a section on line 6—6 of Fig. 3; Fig. 7 is a rear view of a guide to be used in connection with said frame; Fig. 8 is a longitudinal view of one of the removable bars 75 serving for the attachment of the fabric to the frame; Fig. 9 is a similar view of a second bar used in connection with said frame; Fig. 10 is a section on line 10—10 of Fig. 7; Fig. 11 is an elevation on line 11—11 of Fig. 80 and Fig. 12 is a section on line 12—12 of Fig. 9.

Referring specifically to the drawing, the auxiliary frame which is to be suspended 85 from or supported on the frame of an embroidery machine of the type of Groebli or Zahn or any other type of embroidering machines is a skeleton frame consisting of bars 1, 2 which are joined together by rods 3, 4 or in any other way, so as to form a 90 frame of substantially rectangular shape. With the Groebli or Zahn type of embroidering machine, this auxiliary frame is supported in the machine so that the bars 1, 2 extend horizontally and longitudinally 95 while the rods 3, 4 form the end pieces thereof and extend vertically. Each of the bars 1, 2 is provided with a number of bores 5, the bores in the two bars being adapted to register with one another. These bores 100 extend transversely throughout the thickness or width of the bars and serve as bearings for rods 6 adapted to extend transversely through the space formed between the bars 1, 2 and parallel to the end rods 105 3, 4. Each rod 6 is composed of two longitudinal separable parts or sections 6', 6" of semicircular cross section having flat and even base surfaces 6' which, when the parts are assembled, are adapted to bear on one 110 another. In length the two parts 6', 6" are so admeasured that when assembled in the

frame they will wholly or partly engage the bearings 5 of the two longitudinal bars 1, 2. The parts 6', however, is made somewhat longer than part 6² so as to extend with one end entirely through and outwardly from the bar 1 which, when the frame is in operative position, will be uppermost. In thickness the two parts 6', 6² are of equal size and so admeasured that when assembled 10 they fit more or less snugly in the cylindrical bores 5 of the bars 1, 2 excepting that the extended portion 6⁵ of the bar 6' is doubled in thickness and made perfectly circular in cross section so as to fit in the cylindrical bore 5 of the bar 1. The outwardly projecting end 6⁴ of bar 6' is of square cross section and serves to receive a small ratchet wheel 7 which has a correspondingly shaped bore 7' engaging said end 6⁴. The part 6' 15 at the point where it is enlarged in thickness forms a shoulder 6⁶ against which rests the corresponding end of the part 6² when assembled in the frame. The piece of fabric F, which is to be embroidered, is attached 20 to the auxiliary frame as follows:

The shorter part 6² of the rod 6 having been removed one edge or end of the fabric F is put around the flat surface 6³ of the part 6', then the part 6² is put in position so 25 as in cooperation with the part 6' to clamp the fabric. Similarly the opposite edge of the fabric is clamped between the parts 6', 6² of a next following rod 6.

Adjacent to the ratchet wheel 7 of each 30 part 6', is arranged a pawl 8 adapted to coöperate with it. This pawl is mounted on a screwbolt 9 which works in a threaded bore 5' provided at one side of each bore 5.

When the parts have been assembled and 35 the longitudinal edges of the fabric clamped between the parts 6', 6² of two opposite rods 6, the part 6' of one of the rods or of both rods are turned around their axes by means of a key (not shown) to be applied to the 40 square end thereof, and thereby the edges or ends of the fabric become wound around the parts 6', 6² of the rods 6 and is stretched to the desired extent.

As will be seen from the drawing, the 45 bores 5 of a bar are not equally spaced apart but are arranged in pairs or so that at one side of a bore there is one close to it and at the opposite side there is a bore farther removed. This enables the arrangement of the 50 rods 6 so that separate pieces of fabric follow closely one another, instead of at greater intervals which would entail loss of space.

Of course instead of this arrangement, the 55 bars 1, 2 may each have a series of bores very close to one another, which will allow any desired spacing between the rods 6 used for one piece of fabric and the rods for separate pieces.

When larger or smaller pieces of goods are 60 to be embroidered, then the rods 6 are ad-

justed accordingly by removing their parts from the particular bores 5 they are in and placing them into bores lying farther or nearer apart. The pawls 8 are accordingly readjusted. 70

As the spacing between two successive rods 6 for separate pieces of fabric may be smaller than the diameter of the ratchet wheels 7, as in the example shown, the wheels 7 of two adjoining rods 6 will overlap one another, that is, one project above the other. In such cases the hubs of the pawls will vary in size or height as shown. 75

When pieces of fabric are used which are cut on a bias, as parts of a lady's waist, then 80 the edges to be clamped by the rods 6 will not be parallel to the said rods but will project at an angle to the latter. In such cases the angular ends F' of the fabric will have to be gathered up to prevent their project- 85 ing over the part of the fabric to be embroidered and thus interfering with the work. To accomplish this we employ a member or guard 10 preferably made of some soft or pliable material such as fabric, 90 the longitudinal edges of which may be reinforced by rods 10'. This guard is about the height of the piece of the fabric or the length of a rod 6 and in width somewhat larger than the distance between two adjoining 95 rods around which the edges of separate pieces of fabric are wound. Now after the pieces of fabric have been properly stretched, such guards are applied over the backs of the wound up edges of two separate but adjoining pieces of fabric, as shown in Figs. 1, 3 and 5, and the ends of the pieces of fabric which may protrude outwardly over the rear face of the fabric are gathered up and concealed below the guard or member 105 10 (Fig. 5).

The guard 10 is held in position by a U-shaped member 11 rotatively borne in a socket 12 fixed to each bar 1 and 2 and the arms of which are adapted in operative position to engage the end portions of the member 10 as in Figs. 1 and 3. A safety lock 13 in form of a hook fulcrumed on the bar 1 at 13' serves to lock the member 11 when in operative position. 110

A rotary hook shaped member 14 fulcrumed at 14' to the bar 1 serves to engage over the ratchet wheel 7 and to lock the rods 6 in position against longitudinal displacement. 115

In order to allow the operator to determine the place where the embroidery is to begin and to accordingly adjust the implements of the machine, we employ a guide or ruler 15 which is in form of a small rectangular skeleton frame to fit over the back of the piece of fabric to be embroidered. This frame is provided with two longitudinal bars 16, 17 arranged parallel to one another and about centrally of the frame. At both 120 130

ends the bars 16, 17 are extended outside of the frame, at one end somewhat a longer distance than at the opposite end. These extended ends are adapted to engage into bores 5 of the bars 1 and 2, which bores may be separate from those marked 5 or may be the same. By reason of the nonsymmetrical construction of the frame 15, the latter, when mounted in the auxiliary frame over the 10 back of the fabric, will extend with its upper edge (in the drawing with its edge adjacent to the longer ends of the bars 16, 17) below the bar 1 a certain distance and indicate the uppermost end of the embroidery 15 design to be embroidered on the fabric. This edge will be visible in front through the more or less transparent material or fabric and the operator guided by it will accordingly adjust the implements of the 20 machine to start the embroidery on a line coinciding with the said edge. The distance between the longitudinal edges of the frame 15 determines the width of the embroidery. If the design is of lesser or larger width a 25 narrower or broader frame is to be used.

It must also be stated that the teeth of the ratchet wheels are of small pitch to enable a fine stretching of the pieces of fabric.

While we have described the details of the 30 construction, we do not wish to restrict ourselves to the same since various modifications may be made by those skilled in the art without departing from the principle of our invention.

What we claim and desire to secure by Letters Patent is:

1. Means for the attachment of separate pieces of fabric on embroidery machines, consisting of a skeleton frame, removable 40 rods, each composed of longitudinal separable sections and rotatively and removably borne in said frame, said separable sections of each rod resting loosely on one another but held together by their engagement in 45 said frame and being adapted to receive between themselves an edge or end of a piece of fabric and means to permit the fine stretching of the fabric.

2. Means for the attachment of separate 50 pieces of fabric on embroidery machines, consisting of a skeleton frame, having a se-

ries of bores in opposite sides, the bores in one side coinciding with those in the opposite side, rods each composed of longitudinal separable sections and rotatively and removably borne in said bores, said separable sections of each rod resting loosely on one another but held together by their engagement in said frame and being adapted to clamp an edge or end of a piece of fabric, 60 and means for permitting fine stretching of said fabric.

3. Means for the attachment of separate pieces of fabric on embroidery machines, consisting of a skeleton frame having a series of bores in opposite sides thereof, rods borne in said bores and each consisting of two longitudinal separable sections loosely resting on top of one another but held together by their engagement in the said bores 65 and adapted to engage an edge or end of the fabric, one section being extended outwardly of the frame, a ratchet wheel mounted on said extended end and pawls removably fastened to said frame to coöperate with said 70 ratchet wheel.

4. The combination with a fabric frame, of removable rods therein for the attachment of separate pieces of fabric, and a guard of pliable material to fit over two adjoining 80 rods to hold the tail ends of the fabric from projecting over the surface of the fabric and tilttable means on said frame to engage said guard and hold the same in position.

5. The combination with a fabric frame, 85 of removable rods thereon for the attachment of separate pieces of fabric, a guard of pliable material to fit over two adjoining rods holding separate pieces of fabric and serving to prevent the tail ends of the fabric 90 from projecting over the face of the fabric, and means for locking said guard in position and consisting of U-shaped members tiltably supported on said frame and means for locking said tilttable members in position. 95

In testimony whereof we affix our signatures in presence of two witnesses.
